UNITED STATES PATENT OFFICE.

JAMES DEVER, OF SIOUX CITY, IOWA.

COAL-LEVELING GATE.

Application filed September 13, 1921. Serial No. 500,338.

To all whom it may concern:

Be it known that I, JAMES DEVER, a citizen of the United States, residing at Sioux City, in the county of Woodbury and State of Iowa, have invented a new and useful Construction of Coal-Leveling Gates, of which the following is a specification.

This invention, which generally relates to improvements in furnace grates, is more especially designed for use in connection with that type of "endless travelling grates" known as "Green chain grate stoker", in which the grate bars move inwardly toward the interior of the furnace, and afford support for the layer of fuel constantly fed to the outer or receiving end of the grate, and thereby moved into the furnace during the progress of combustion.

My invention is especially directed to improvements in the usual sliding fuel door or gate mechanism that is located over the feed opening of the furnace and with which is connected means for effecting vertical adjustment thereof to control the thickness of the fuel as it is being supplied from the hopper or stoker cooperative therewith.

Primarily my invention seeks to provide an improved coal leveling gate whose construction is so designed that the said gate is absolutely unburnable and one which will not warp from the heat or fire.

My invention also has for its purpose to provide a gate of the character stated, capable of such ready adjustment, relatively to the fuel infeed passage to the furnace, that when the furnace is fired up and thoroughly heated throughout, the coal ignites as soon as it passes under the inside wall of the gate, and it also operates to effect a perfect leveling of the coal across the grates as the fuel is carried inward thereon.

With other minor objects in view that will become apparent as the detailed description of my invention is proceeded with, my said invention embodies, in a coal leveling gate of the kind stated the peculiar arrangement and novel combination of parts fully stated in the following description, specifically pointed out in the appended claims and illustrated in the accompanying drawing, in which:

Figure 1 is a central vertical section of my improved coal leveling gate, so much of an endless traveling furnace grate construction, the furnace and the fuel feed hopper being

shown as necessary to illustrate a practical application of my invention.

Figure 2 is a detail section taken on the line 2—2 of Figure 1, looking in the direction of the arrow, the gate structure being in elevation, the movable grate portions being omitted.

Figure 3 is a perspective view of a portion of my improved construction of leveling gate.

Figures 4 and 5 are cross sections thereof taken respectively on the lines 4—4 and 5—5 of Figure 3.

Figure 6 is a detail view of the I-beam.

Figure 7 is a detail perspective view of one of the end tiles of the outside course of tiles of the gate body.

In the drawings, 1 designates a portion of one of the side walls of the furnace, 2 a portion of the guide bars which are of the continuous ring or loop type and 3 the grate bars. 4—4 designates transverse rods to which the grate bars are attached and which carry the friction rollers 20 (see Figure 2). 5 is the feed hopper at the forward end of the furnace from which the fuel is taken by the endless grate and carried through the feed opening 6 into the furnace.

The parts mentioned being of a well-known construction and forming no part of my invention will not be hereinafter further referred to in detail.

My invention especially relates to the improved sliding door or gate construction that is located over the feed opening 6 of the furnace with the lower edge thereof, a short distance above the grate and which, as hereinafter stated, is made adjustable to control the thickness of the layer of fuel as the said fuel is carried through the said feed opening 6.

The door or gate of my construction consists of an I-beam 7, in practice, seven and one-half feet long, such length accommodating a stoker eight feet wide.

Cooperative with the beam 7 are an outside and an inside course of tiling, the said courses being designated respectively 8 and 9. Each course of tiling is composed of tile blocks, each of said blocks being preferably twelve inches high and twenty-four inches long and the said blocks are closely placed end to end to constitute the outer and inner faces of a gate eight feet long, the said blocks being held in rigid relation by reason

of their attachment to the single I-beam 7, and with each other, as will be presently further explained.

The inside course of tiles 9 is fitted tightly 5 up against the body or web of the I-beam and the said course of tiles 9 is supported upon and is connected with the said I-beam but it is spaced one inch, more or less, from the body of the said beam and the outside course 10 of tile lining 8.

As is best shown in Figures 4 and 5, the outside base portion at the bottom of the beam 7 is cut away to form a narrow flange 80 along the full length of the beam 7 and 15 the said flange in practice, extends a sufficient width, preferably one-half of an inch, to constitute a support for fitting within the horizontal bearing grooves 81 in that side of the tile members 8 which face and 20 bear against the beam 7.

Each tile block of the inner series has a horizontal bearing groove 90 to receive 25 the outer or front portion of the wide base 71 of the beam 7, the said portion, in practice, extending one and one-half inches from the web of the beam.

The tile lining 8 is held one inch away 30 from the tile lining 9 by a series of tubular spacers 10, and the whole structure is rigidly 35 connected by a series of stay rods 11 that pass transversely through both the inner and outer tile blocks, and the spacers 10.

An upper and a lower set of tie rods are 35 provided along the entire series of tile blocks, and the upper set passes through 40 apertures 75 in the web of the I-beam.

Some of the rods 11 pass through the 45 liner blocks 9 through the I-beam and the other liner blocks 8, as is best shown in 50 Figures 4 and 5, by reference to which it will be observed the rod heads are buried one 55 inch or more or less within sockets 95 in the outer face of the blocks 9, and the said heads are covered by fire-clay or asbestos 60. The outer ends of the rods 11 extend into 65 sockets 81 in the front liner blocks 8 and are made fast by clamp nuts 85.

The tile blocks, in practice, are preferably 50 five inches thick, and each end tile of the outside course of the tiling has a vertical cut 55 out portion 83 that merges with an undercut horizontal socket 84, such formation of the end ones of the outside course of tiles allowing for their ready connection with the 60 casting or hanger members 12, by which the gate is raised or lowered, and which join with the usual raising and lowering means provided in the top of chain grate stokers stated, and generally indicated at 13—13 of 65 Figures 1 and 2 of the drawings.

14 designates an asbestos joint or filling which fits the space between the separated inner and outer course of the tile.

From the foregoing description, taken in 65 connection with the accompanying drawings,

the complete construction, the manner of its application and use and the advantages of my coal gate will be readily apparent to those familiar with the manufacture and use of endless chain grate stokers.

By forming the gate of the body having an I-beam as the base, and with the inner and outer faces composed of a series of tile blocks that are substantially rigidly attached to the I-beam and to each other, the gate 70 is possessed of the required strength and durability, and since no metal parts are in direct contact with the fuel and the heat at the fuel opening to the furnace, the feed of coal may be maintained absolutely level 80 across the grate and the danger of the gate burning or warping reduced to the minimum.

What I claim is:—

1. In a furnace provided with a fuel opening, the combination with an endless chain grate forming the floor of the said opening; of a gate arranged to control the passage of fuel through the said opening, the said gate comprising a body composed of an I-beam core, an inner course of tiling blocks held in close end to end relation, the said inner course of tiling blocks having a horizontal groove along one side for interlocking with the base flange at the corresponding side of the I-beam, an outer course of tile blocks held in close endwise relation and having a longitudinal groove for engaging the corresponding edge of the base flange of the beam, spacers interposed between the beam and an adjacent course of tiling, and cross tie rods that pass through 95 the two courses of tiling, some of the said tie rods passing through the web of the I-beam.

2. In a furnace provided with a fuel feed opening, the combination with an endless chain grate forming the floor of the said opening; of a gate arranged to control the passage of fuel through the said opening, 110 the said gate comprising a body composed of an I-beam, an outer course of tiling blocks held in close end to end relation, the said course of tiling blocks having a horizontal groove for interlocking with the base flange on the adjacent side of the beam, an inner course of tiling blocks held in close 115 endwise relation and having a longitudinal groove for engaging the adjacent edge of the base flange of the beam, spacers in position between the outer course of tiling and the inner course, cross tie rods that pass through the inner and outer courses of tiling, some of the said tie rods passing through 120 the web of the I-beam, the outer course of tiling having sockets, and means for raising and lowering the gates including hangers for engaging the sockets in the outer course 125 of tiling.

JAMES DEVER.
